UNITED STATES PATENT OFFICE.

FRANK A. NIEBERDING, OF CLEVELAND, OHIO; MARGARET H. NIEBERDING ADMINISTRATRIX OF SAID FRANK A. NIEBERDING, DECEASED.

HEATER.

Application filed September 27, 1923. Serial No. 665,250.

This invention relates to gas heating stoves of the class wherein elongated artificial fuel elements or so-called "radians" are employed. In stoves of this class, efficiency depends largely upon the expanse of the direct radiating surface of the fuel elements, and the attractiveness and effectiveness of the device result, in a large measure, from the conspicuousness of the radians. This is because the glow or direct rays from the fuel elements is conducive of cheerfulness, having as is well recognized, a psychological effect of warmth upon the observer.

It is, therefore, the fundamental purpose of the invention to produce a gas heating stove of the aforesaid character that is very attractive of appearance and wherein the radians are so arranged that they will radiate their heat directly throughout a very wide angle and will be visible from practically any point forwardly of the front plane of the stove.

Another object is to provide a very substantial, rigid, compact, comparatively simple and inexpensive construction for stoves of the aforesaid class.

Another object is to provide a burner which will effect a very uniform distribution of gas from a central point to all the radians and wherein the control valve is situated at one side of the front of the stove so as to be protected from the intense heat of the radians and avoid discomfort to the manipulator of the valve and render more convenient the lighting of the stove.

A further object is to provide a shell for use with a stove of the aforesaid class when it is located adjacent a wall, or more especially when it occupies a fire place opening, and which imparts a finished appearance to the structure.

The several objects above set forth, with others hereinafter appearing, are attained in the embodiment of the invention illustrated in the accompanying drawings wherein Fig. 1 is a front elevation of my improved gas heating stove; Fig. 2 is a sectional plan view of the same; Fig. 3 is a central vertical section from front to rear through the stove; while Figs. 4 and 5 are, respectively, a front elevation and sectional plan showing the stove with the finishing shell applied thereto and occupying the opening of the fire place.

Describing the invention by the use of reference characters, 1 represents a front frame that is made of top and side members, the side members being connected a suitable distance above their lower ends by a cross bar 2, this bar thus constituting the bottom member of the frame. A curved wall 3, which is preferably formed from a single piece of sheet metal, has its lateral edges secured, as by screws 4, to the side members of the frame 1. This curved wall 3 with a top wall 5, constitutes the stove casing, the top wall being shown as having a flange 6 depending from its forward edge which is secured by fastening means 7 to the top member of the front frame. The curved edge of the top wall is flanged downwardly about, and suitably connected to, the upper edge of the wall 3, as indicated at 8 in Fig. 3.

A ledge 10 is secured, as by bolts 11, to the inner side of the curved wall 3 a proper distance from its lower edge and extends approximately from one lateral edge thereof to the other. The forward edge of the ledge is flanged upwardly, as shown at 12, and rearwardly of said flange it supports a fire back 13 of fire clay or other suitable refractory material which is preferably made up of sections, three of such sections being shown, the adjacent or meeting edges of the middle and side sections being formed to interlock, as indicated at 14. The forward edges of the side sections are thickened to provide flanges 15. It will be noted that the bottom of the fire back 13 is reduced in width to fit within the channel between the flange 12 and the opposed portion of the casing wall 3, and the top of the fire back is similarly formed to fit within a channel similarly provided between the front depending flange of a Z-bar 16 and the opposed portion of the casing wall 3. The Z-bar 16 is suitably connected to the wall 3, as by bolts 17, the bar being substantially coextensive with the ledge 10. It will be noted that the reduced upper end of the fire back 13, and the channel into which it fits, are of sufficient depth to permit the sections of the back to be lifted enough to disengage their lower ends from behind the flange 12 of the ledge 10 when it is desired to remove the fire back from the casing.

A canopy 20 occupies the upper portion

of the casing and is shown as having its front edge provided with a flange 21 that may be secured by fastening means or screws 22 to the top member of the front frame 1, and the depending wall 22 of the canopy is substantially concentric with the rear wall 3 of the casing. A horizontal flange 23 extends about the lower edge of the canopy. Secured to the front portion 10 of the top wall of the canopy 20 is the rear edge of a hood 25 which projects out through the opening of the front frame 1. A top reflector 27 is disposed within the canopy 20 and has a flat vertical wall 28 which extends across the front frame beneath the hood. In order to impart stiffness to the reflector, its rear curved edge is flanged upwardly at 29.

A curved burner 30 occupies the lower portion of the casing, forwardly of the lower edge of the fire back 13, and it is supported through integral lugs 31 from lugs 32 that are secured to the rear wall 3, as by bolts 33. The body portion of the burner may be made up of top and bottom shells 34 and 35, respectively, which are suitably connected together, and a distributing plate 36 is arranged inside the body 30 of the burner and is provided with suitably shaped openings to properly distribute the gas, as it issues through the mixing tube 38, throughout the length of the burner so that all radiants will receive substantially equal amounts of gas. As to structural characteristics, my present burner is practically the same as that shown in my copending application, Serial No. 532,551, filed January 30, 1922. The top shell 34 has jet openings 40 which contain burner tips 41, similar to those shown in the application just referred to, and supported above each jet opening and properly positioned with respect thereto by lugs 42, are artificial fuel elements or radiants 43. The tops of the radiants are retained against forward displacement for a curved bar 44 supported by brackets 45 from the vertical wall 22 of the canopy 20.

A bottom plate or reflector 46 is fitted within the casing forwardly of the lower ends of the radiants and is supported and properly positioned with respect thereto by a flange 48 that rises from the cross bar 2, and by brackets 49 which extend from the burner. The curved edge of the plate or reflector 46 is spaced from the radiants 43 to permit the passage of air upwardly between the plate and radiants in sufficient quantity to promote proper combustion.

A hearth plate 50, having a skirt 52, is supported from the cross bar 2 by a flange 53 which is engaged within a slot 54 of the cross bar.

The mixing tube 38 is preferably extended forwardly and laterally from the central portion of the burner so that the operating

handle 55 of a valve 56 which is supported in operative relation to the forward end of the mixing tube, is situated at one side of the front of the stove where it may be conveniently manipulated with the right hand while lighting the stove with the left and where it will be out of range of the intense heat from the radiants to avoid discomfort to the operator when turning the handle to control the fire. In accordance with the usual practice, a supply pipe 57 is connected to the valve 56.

The rear portion of the casing may be supported by a single leg 58 that is secured to the center of the lower edge of the rear wall 3, thus affording the very desirable three-point suspension for the stove, insuring its setting firm at all times.

A flue collar 60 is applied to the top wall 5 in register with an opening 61 and a stove pipe 62 is shown applied to the collar. Obviously, the flue connection may be made in the rear wall 3 above the Z-bar 16 where circumstances are such as would make the latter arrangement preferable to that shown. An opening or openings, 20^a, may be made in the top wall of the canopy 20 for a purpose which shall presently appear.

In the operation of the stove, the products of combustion follow the radiants 43 upwardly and are discharged into the top of the casing from which they are drawn off through the flue, and should any escape beneath the flange 23 of the canopy, they are drawn into the canopy about the edge of the reflector 27 and are recovered through the opening or openings 20^a.

Because of the curved arrangement of the radiants, they may be seen from practically any point forwardly of the front plane of the stove, and for the same reason they distribute their heat by direct radiation throughout a very wide angle.

When the stove is positioned adjacent a wall, or more especially, when placed within a fire place opening 65, as shown in Figs. 4 and 5, it may be equipped with a shell 66 comprising top and side walls which are shown as having their forward edges fitted to the frame 1 and their rear edges in a vertical plane slightly back of the rearmost point of the curved wall 3 so that said edges may engage against the wall or against the back of the fire place opening. When used in a fire place provided with the usual flue or chimney, the flue 62 may be dispensed with and the products of combustion may escape through openings or notches 67 that are formed in the top wall of the shell adjacent its rear edge and carried off through the chimney of the fire place.

Having thus described my invention, what I claim is:

1. A heater of the character set forth comprising an open front frame, a rear

wardly curved fireback extending from one side member of the frame to the other, thereby to provide an arcuate cavity which opens through said frame, a curved burner

5 adjacent to and forwardly of the fireback, and a continuous series of radiants disposed in front of the fireback and in operative relation to the burner and extending from a point adjacent one side member of the front frame to a point adjacent the other side member thereof.

2. A heater of the character set forth comprising an open front frame, a rearwardly curved back wall extending from 15 one side member of the frame to the opposite side member thereof, the lateral edges of the back wall being secured directly to the front frame, a fireback conforming to the shape of the back wall and disposed forwardly thereof and substantially co-extensive therewith in a lateral direction, a curved burner disposed forwardly of the lower end of the fireback, and a continuous series of radiants supported forwardly of the fireback and in operative relation to the burner and extending from a point adjacent one side member of the front frame to a point adjacent the opposite side member thereof.

3. A heater of the character set forth comprising an open front frame, a fireback extending rearwardly from one of the side members of the frame across the frame and to the other side member thereof, a burner disposed forwardly of the lower portion of the fireback and extending substantially from end to end thereof, a continuous series of radiants supported in operative relation to the burner approximately throughout the length thereof, and top and bottom reflectors extending from the corresponding members of the front frame rearwardly to within a short distance of the radiants.

4. A heater of the character set forth comprising an open front frame, a back wall extending from one side member of the frame to the other and having its central portion spaced rearwardly a suitable distance from the plane of the front frame, a burner disposed forwardly of and following the contour of said back wall from a point adjacent one of the side members of the frame to a point adjacent the other side member thereof, a continuous series of radiants disposed above and in operative relation to the burner and substantially co-extensive in length therewith, and top and bottom reflectors extending inwardly from the corresponding members of the front frame to within a short distance of the radiants, the radiants and said reflectors constituting the walls of a cavity which opens through the aforesaid front frame.

5. A heater of the character set forth comprising an open front frame, a back wall

spaced rearwardly from the front frame and having its side portions extended forwardly and connected to the side members of said frame, a top wall secured to and extending rearwardly from the top of the front frame 70 and joining the back wall about its side and rear portions, a fireback supported by and forwardly of the back wall and extending from one of the side members of the front frame to the other, a burner supported by 75 the back wall forwardly of the lower portion of the fireback, a continuous series of radiants supported forwardly of the fireback and in operative relation to the burner, a canopy secured to the rear side of the top 80 portion of the front frame and extending rearwardly therefrom to within a short distance of the upper ends of the radiants, means carried by said canopy for maintaining the radiants in upright position, and 85 top and bottom reflectors extending rearwardly from the respective corresponding members of the front frame, the rear edge of the bottom reflector being spaced a short distance from the lower ends of the radiants, 90 and the rear edge of the top reflector being spaced a suitable distance forwardly of the rear wall of the canopy.

6. A heater of the character set forth comprising an open front frame, a back wall 95 having its central portion spaced a suitable distance rearwardly of the frame and its side portions extended forwardly and connected to the side members of said frame, a top wall having its forward edge connected to the top of the front frame and its side and rear edge portions joined to the top of the back wall, a fireback supported by and forwardly of the back wall and extending from one of the side members of the 100 front frame to the other, a burner supported in front of the lower portion of the fireback, a series of radiants disposed in operative relation to the burner, said series of radiants being substantially coextensive with the fireback in a lateral direction, a canopy secured to and extending rearwardly from the top member of the front frame below the aforesaid top wall, the rear wall of the canopy being spaced a suitable distance from the 105 tops of the radiants, and top and bottom reflectors extending rearwardly from the corresponding members of the front frame, the rear edge of the bottom reflector being spaced a comparatively short distance from 110 the lower ends of the radiants while the corresponding edge of the top reflector reposes within the rear wall of the canopy.

7. A heater of the character set forth comprising an open front frame, a back wall 115 having its central portion spaced a suitable distance rearwardly of the frame and its side portions extended forwardly and connected to the side members of the frame, a top wall having its forward edge connected 120

to the top of the front frame and its side and rear edge portions joined to the top of the back wall, a fireback supported by and forwardly of the back wall and extending from one of the side members of the front frame to the other, a burner supported in front of the lower portion of the fireback, a series of radiants disposed in operative relation to the burner, a canopy secured to and extending rearwardly from the top member of the front frame below the afore-said top wall, the rear wall of the canopy being spaced a suitable distance from the tops of the radiants, top and bottom reflectors extending rearwardly from the corresponding members of the front frame, the rear edge of the bottom reflector being spaced a comparatively short distance from the lower ends of the radiants while the

corresponding edge of the top reflector reposes within the rear wall of the canopy, and a hood supported within the upper end of the front frame and projecting forwardly therefrom. 20

8. A heater comprising an open front casing, a burner within the casing, said burner having its central portion spaced rearwardly from the open front of the casing and its ends projecting forwardly to within a comparatively short distance of the sides of the open front, and a continuous series of radiants supported in operative relation to the burner and coextensive in length therewith. 25

30 In testimony whereof, I hereunto affix my signature. 35

FRANK A. NIEBERDING.
